DESIGN FOR A PLAQUE OR SIMILAR ARTICLE

Charles F. Sargent, New Haven, Conn., assignor to Sargent & Company, New Haven, Conn., a corporation of Connecticut

Application May 8, 1940, Serial No. 92,217

Term of patent 3½ years

To all whom it may concern:

Be it known that I, Charles F. Sargent, a citizen of the United States, residing in New Haven, in the county of New Haven and State of Connecticut, have invented a new, original, and ornamental Design for a Plaque or Similar Article, of which the following is a specification, reference being had to the accompanying drawing, forming part thereof, in which

Fig. 1 is a front elevational view of a plaque or similar article embodying my design; and

Fig. 2 is a side elevational view thereof.

The essential features of my design reside in the figure shown in full lines.

I claim:

The ornamental design for a plaque or similar article, substantially as shown and described.

CHARLES F. SARGENT.
